LOOP CONTROL FOR TOROIDAL COIL WINDING MACHINES

Henry E. Cradduck, Amesbury, Mass., assignor to
 Western Electric Company, Incorporated, New
 York, N. Y., a corporation of New York

Application August 10, 1951, Serial No. 241,346

7 Claims. (Cl. 242—4)

1

This invention relates to toroidal coil winding machines and more particularly to apparatus for controlling the necessary loop in the wire during the operation cycles of toroidal coil winding machines.

In winding coils of wire on toroidal cores the supply of wire is placed on a winding ring or shuttle which travels at a constant rate about its axis through the core. The conventional wire guide travels on a track formed at one side of the shuttle pulling a length of wire from the shuttle as it travels away from the core to form the next convolution of the wire about the core. This length of wire is formed into a loop as the wire guide travels toward the core and unless the loop of wire is held taut and guided throughout its travel, the convolution formed thereof may overlay previous convolutions on the core or it may be inaccurately positioned on the core where subsequent convolutions are to be wound. Furthermore, unless the wire in the loop is held taut, it may be jerked about the core resulting in breakage of the wire. The patents to A. J. Dowd, 2,367,489, and R. M. Conklin, 2,425,511, disclose steps which have been taken in the art to control the loop in toroidal coil winding machines. The structures in both of these patents employ stationary and movable pressure pads between which the wire in the loop must be drawn while advancing toward the core. These structures have eliminated various difficulties but they contain certain features which are not suitable for winding finer wires, one being the frictional contact with the wire as it passes between the pressure pads, another being the presence of uncontrolled intervals while the loop is travelling toward the core.

An object of the present invention is to provide a wire guide in a toroidal coil winding machine which is simple in structure yet highly efficient in controlling the wire loop and maintaining it taut throughout the formation of each convolution on a core.

With this and other objects in view, the invention comprises a wire guide in a toroidal coil winding machine including a member to travel with the shuttle to remove the necessary length of wire for forming a convolution on a core and a trailing element movable relative to the member to maintain the wire taut.

The conventional toroidal coil winding machine selected to illustrate the invention has an annular shuttle with a track on one side thereof to support the leading member of the wire guide so that it will travel with the shuttle or slide

2

thereon under the control of the wire to remove a length of wire from the shuttle during each cycle thereof. In one embodiment of the invention the trailing element is arcuate in general contour to partially conform to the shuttle, pivoted at its leading end to the member and having a pin at its trailing end over which the wire travels so that the element will be affected by centrifugal force, holding the wire taut at all times but being drawn inwardly by the wire closely adjacent the shuttle as it travels through the toroidal core. In another embodiment of the invention a resilient element carried by the member maintains the wire taut at all times.

Other objects and advantages will be apparent from the following detailed description when considered in conjunction with the accompanying drawings wherein:

Fig. 1 is a side elevational view of a toroidal coil winding machine embodying one species of the invention, illustrating the start of the winding of a convolution;

Fig. 2 is similar to Fig. 1, illustrating the position of the wire guide as it travels through the core;

Fig. 3 is a schematic illustration of various positions of the leading end of the wire guide relative to the core; and

Fig. 4 is a side elevational view of another species of the invention.

Referring now to the drawings, the toroidal coil winding machine selected to illustrate the invention includes the conventional shuttle or winding ring 10 constructed with a removable section (not shown) so that it may be positioned to travel through successive toroidal core 11 and be supported with its teeth 12 interengaging a drive gear 14 and idler gears 15. The core 11 is supported by jaws 16 of the conventional type of mechanism which will rock the core about its center to distribute the convolutions of wire 17 uniformly about portions of the core. Prior to the winding operation the shuttle 10 is provided with a supply of the wire 17.

The species of wire guide, shown in Figs. 1 and 2, include a slider indicated generally at 20 having spaced portions 21 and 22 connected by a resilient member 24. The portions 21 and 22 have grooves in their inner surfaces to interengage a track 23 formed on the side of the shuttle 10. The grooves and track may be of a dovetail contour to control the path of travel of the slider 20. The resilient member 24 provides sufficient force to create frictional contact between the portions of the slider and the track,

urging the slider to travel with the shuttle yet permitting it to slide on the track under the control of the wire 17. The nose or leading end 25 of the portion 21 is grooved in the conventional manner so that it will remove lengths of wire from the shuttle and guide them about the core.

An arcuate element 28 is pivoted at 29 to the trailing end of the slider or the portion 22 thereof, the contour of the element being such that it may partially conform to the shuttle while travelling through the core. A pin 30 is mounted in the trailing end of the element and positioned so that the wire 17 will travel over the pin at all times. Although the element 28 is capable of being affected by centrifugal force to hold the wire taut during the major portion of the operation of the winding machine, a resilient element 32 fixed at one end to the portion 22 of the slider 20 and looped at the other end 33 to engage a pin 34 of the element 28, urges the element outwardly during the slower starting and stopping speeds of the shuttle.

Considering now the operation of this species of wire guide during normal operation of the toroidal coil winding machine, let it be assumed that prior to starting the machine, the leading end of the wire has been attached to the core in a conventional manner, extending from the shuttle about the pin 30 and about the nose 25 of the portion 21 of the slider 20. The machine may then be started, driving the shuttle 10 counterclockwise. During travel of the shuttle the slider will tend to move with it, under the control of wire 17. By viewing Fig. 2 it will be observed that a convolution has been completed on the core and that a new length of wire is being withdrawn from the shuttle to form the next convolution on the core. Fig. 3 illustrates various positions of the nose of the guide while pulling the wire from the shuttle. During this interval of operation, the pull on the wire to remove it from the shuttle is sufficient to draw the element 28 inwardly, closely adjacent the shuttle so that it will travel through the core. This condition will persist until the full length of wire has been removed from the shuttle at which time the nose 25 of the slider will be at its maximum distance from the core and the element 28 will have travelled through the core. As the slider continues its travel toward the core, it no longer holds the wire taut and a loop necessarily forms in the wire as in the conventional machine. This loop will be under the control of the element 28 at all times due to the effect of centrifugal force on the element proportional to the speed of rotation of the shuttle to hold the wire taut. As an added precaution, the resilient element 32 assures outward movement of the element 28 about its pivot 29 to maintain the wire taut during the starting and stopping intervals of the shuttle. While the machine is operating at full speed, the element 28 affected by centrifugal force creates an outward pull on the loop, holding it taut and under complete control at all times during the complete formation of each convolution on the core, removing entirely any jerking action during the formation of the convolutions and minimizing the frictional resistance on the wire.

The species of the invention shown in Fig. 4 are the same in every detail to the species shown in Figs. 1 and 2 excepting the trailing element carried by the slider and like reference numerals identify those identical features in all three figures. The element 48 in Fig. 4 is formed of re-

silient material with its leading end secured to the member 22 of the slider 20 at 49 and its trailing end supporting a guide pin 50 for the wire 17 to travel over. The normal contour of the element is such that it will apply suitable force on the wire at all times to hold it taut. This species of the invention has proven very efficient in winding the finer wires on cores. The necessary force in the element is determined by the strength of the wire to be wound as the element must be pulled toward the shuttle as the wire in the loop is wound on the core. Also the resilient element is affected by centrifugal force and this condition may be varied for winding heavier wires by increasing the width of the element or by adding a suitable mass thereto.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

- 25 1. A wire guide in a toroidal coil winding machine having an annular shuttle, for wire to be wound on a toroidal core, driven at a constant speed through the core and having a track at one side thereof, the wire guide comprising a slider mounted on the track and having a groove for the wire at its leading end to remove successive lengths of wire from the shuttle and guide them about the core, and an element swingably connected at its leading end to the slider and having its trailing end formed to engage the lengths of wire, whereby the element will be urged to swing outwardly by centrifugal force to maintain the portions taut throughout the formation of the convolutions thereof about the core.
- 30 2. A wire guide in a toroidal coil winding machine having an annular shuttle, for wire to be wound on a toroidal core, driven at a constant speed through the core and having a track at one side thereof, the wire guide comprising a slider mounted on the track and having a groove for the wire at its leading end to remove successive lengths of wire from the shuttle and guide them about the core, and an arcuate element positioned to follow the slider, means to pivotally secure the leading end of the element to the trailing end of the slider whereby the element may swing outwardly by centrifugal force during rotation of the shuttle, and means disposed at the trailing end of the element to engage the wire and hold it taut.
- 35 3. A wire guide in a toroidal coil winding machine having an annular shuttle, for wire to be wound on a toroidal core, driven at a constant speed through the core and having a track at one side thereof, the wire guide comprising a slider mounted on the track and having a groove for the wire at its leading end to remove successive lengths of wire from the shuttle and guide them about the core, and an element swingably connected at its leading end to the slider and having its trailing end formed to engage the lengths of wire, whereby the element will be urged to swing outwardly by centrifugal force to maintain the portions taut throughout the formation of the convolutions thereof about the core and a resilient member carried by the slider to normally urge the element to swing outwardly.

4. A wire guide in a toroidal coil winding machine having an annular shuttle, for wire to be wound on a toroidal core, driven at a constant speed through the core and having a track at one side thereof, the wire guide comprising a slider mounted on the track and having a groove for the wire at its leading end to remove successive lengths of wire from the shuttle and guide them about the core, and an arcuate element having its leading end pivotally connected to the trailing end of the slider and its trailing end formed to engage the lengths of wire whereby the element will swing outwardly by centrifugal force to hold the wire taut and will be swung inwardly by the wire to travel through the core closely adjacent the shuttle when each length of wire is wound on the core.

5. A wire guide in a toroidal coil winding machine having an annular shuttle, for wire to be wound on a toroidal core, driven at a constant speed through the core and having a track at one side thereof, the wire guide comprising a slider mounted on the track and having a groove for the wire at its leading end to remove successive lengths of wire from the shuttle and guide them about the core, and an arcuate element having its leading end pivotally connected to the trailing end of the slider and its trailing end formed to engage the lengths of wire whereby the element will swing outwardly by centrifugal force to hold the wire taut and will be swung inwardly by the wire to travel through the core closely adjacent the shuttle when each length of wire is wound on the core, and a spring to normally urge the element outwardly during slower starting and stopping rotary cycles of the shuttle.

6. A wire guide in a toroidal coil winding machine having an annular shuttle, for wire to be wound on a toroidal core, driven at a constant

speed through the core and having a track at one side thereof, the wire guide comprising a slider mounted on the track and having a groove for the wire at its leading end to remove successive lengths of wire from the shuttle and guide them about the core, and an element having its leading end swingably connected to the slider and urged to swing outwardly during rotation of the shuttle, the trailing end of the element being formed to engage the lengths of wire to hold them taut.

7. A wire guide in a toroidal coil winding machine having an annular shuttle, for wire to be wound on a toroidal core, driven at a constant speed through the core and having a track at one side thereof, the wire guide comprising a slider mounted on the track and having a groove for the wire at its leading end to remove successive lengths of wire from the shuttle and guide them about the core, and a resilient element having its leading end connected to the slider and having a guide member for the wire supported by the trailing end thereof, the resilient element being adapted to be flexed inwardly by the wire to travel through the core and normally swingable outwardly by its inherent force assisted by centrifugal force to cause the guide member to engage the lengths of wire and hold them taut.
